UNITED STATES PATENT OFFICE.

JAMES P. O'CONNELL, OF CROMPTON, RHODE ISLAND, ASSIGNOR OF ONE-HALF TO
EDGAR L. MERROW, OF MALDEN, MASSACHUSETTS.

KNOT-TYING DEVICE.

1,051,155.

Specification of Letters Patent. Patented Jan. 21, 1913.

Application filed December 30, 1909. Serial No. 535,709.

To all whom it may concern:

Be it known that I, JAMES P. O'CONNELL, of Crompton, in the county of Kent and State of Rhode Island, have invented certain new and useful Improvements in Knot-Tying Devices; and I do hereby declare the following specification, taken in connection with the accompanying drawings, forming a part of the same, to be a full, clear, and exact description thereof.

The invention relates to an improved device for speedily tying the ends of yarn or thread together, and is particularly adapted for use by the operators of doubling, twisting, spooling, winding and similar machines.

The principal object of the invention is to provide a simple and inexpensive device of this character which can be conveniently supported upon the fingers of the operator and which is provided with means for cutting the ends of the yarn, after the knot is tied, into uniform lengths as well as to any desired length.

Another object of the invention consists in providing a device of this character with removable cutting means.

To these ends the invention consists in the novel construction and combination of parts hereinafter set forth and claimed.

In describing the invention in detail reference will be made to the accompanying drawings, in which—

Figure 1 is a perspective view showing my improved knot-tier in one hand of the operator and the manner of holding the broken ends of the yarn in the other hand, the knot-tier being in its first position upon the yarn. Fig. 2 is a similar view illustrating the second position of the knot-tier with the yarn looped around the same. Fig. 3 is a similar view illustrating the third position of the knot-tier with the yarn in position for the loop to be slipped off of the knot-tier. Fig. 4 is a similar view illustrating the first position of the knot-tier after the loop has been slipped off of the end thereof and the knot completed. Fig. 5 is a front view of my improved knot-tier in its preferred form. Fig. 6 is an edge view of the same. Fig. 7 is a front view of a modified form. Fig. 8 is an edge view of

the same. Fig. 9 is a sectional view on line $x-x$, Fig. 8. Figs. 10, 11, 12, 13, and 14 are detail views.

Referring to Fig. 5, 1 represents the body portion of the knot-tier which is formed out of a piece of flat steel into a suitable shape to fit comfortably in the hand of the operator. In one end of the body portion 1 is loosely mounted a ring 2 by means of which the device may be supported on one of the fingers of one hand of the operator without interfering with the use of said hand for other purposes. Adjacent the other end said body portion 1 is cut out to form an elongated longitudinal opening 3 having side portions 4 and 5 and a rounded end portion 6, as shown in Figs. 5 and 7. That part of the body portion 1 in which the opening 3 is formed is bent into a concavo-convex form as shown in Figs. 6 and 8.

Removably mounted in a suitable slot in the end portion 6 is a knife 8 which extends into the outer end of the opening 3 and is provided with a circular cutting edge 9 upon one side thereof. The knife 8 is arranged at an angle to the body portion 1 and is held in position in the end portion 6 by a screw 10.

As shown in Figs. 6 and 8, the upper surface of the side portion 4 is provided with a raised portion 11 adjacent the free end of the knife 8 and the upper surface of the side portion 5 is provided with a low portion 12 adjacent the free end of said knife 8 for a purpose to be hereinafter described.

The manner in which the device is used will now be described, reference being had to Figs. 1, 2, 3, and 4 of the drawings. The knot-tier is held in the right hand, the little finger passing through the ring 2. The broken ends of the yarn 13 are now taken by the fingers of the right hand and passed over the thumb and first finger of the left hand and gripped by the remaining fingers of said left hand. The knot-tier is then placed upon that portion of the yarn 13 which passes from the thumb to the first finger, as shown in Fig. 1. The free end of the knot-tier is now moved downward and around the yarn 13 by twisting the right hand so as to turn said knot-tier over and bring the convex surface of the end portion

uppermost, thereby forming a loop of the yarn 13 upon said knot-tier, as shown in Fig. 2. The portion 14 of the yarn 13 which extends from the loop which has been formed on the knot-tier is now carried across the top of the opening 3 on to the side portion 5 at the rear of the free end of the knife 8. If now said portion 14 of the yarn 13 is advanced by sliding the same along the upper surface of the side portion 5, when it reaches the low portion 12 of said side it will pass beneath the free end of the knife 8 and into the position shown in Fig. 3. The knot-tier is now drawn away from the left hand, which causes the loop which has been formed upon said knot-tier to slide along the side portions 4 and 5 toward the free end of the tier. As said loop passes up on to the raised portion 11 of the side portion 4 it clears the free end of the knife 8 and is free to pass entirely off of the knot-tier and form the knot, as shown in Fig. 4. After the knot has been formed the knot-tier is given a quick forward rotary movement and the waste ends of the yarn 13 are severed by means of the cutting edge 9 and the knot completed.

As will be seen, the length of the ends of the yarn after the knot is completed depends upon the distance from the cutting edge 9 to the outer edge of the side portion 4 at the point where the knot lies when the yarn is severed, so that by making the knife 8 wider and its cutting edge nearer the inner edge of the side portion 5, the length of the ends of the yarn will be increased. Thus by varying the width of the knife 8 the length of the ends of the yarn when the knot is completed may be varied as desired.

Fig. 7 shows a modified form of the knot-tier in which the knife 8' is made from a round, instead of from a flat, piece of stock, in which case the knife is mounted and secured in a hole, instead of a slot, in the end portion 6. The cutting edge 9' in this form is considerably shorter than in the preferred

form shown in Fig. 5, but it is sufficiently long for fine yarns.

What I claim as my invention and desire to secure by Letters Patent is:

1. A device of the character described comprising a flat body portion having one end provided with a longitudinally extending bend and a knife removably mounted in said bent portion.

2. A device of the character described comprising a flat body portion, an elongated inclosed opening adjacent one end and a knife removably mounted in one end of said body portion and having the free end thereof extending into said opening.

3. A device of the character described comprising a flat body portion provided with an elongated longitudinal opening and a bend adjacent one end, and a knife removably mounted in said body portion and having the free end thereof extending into the outer end of said elongated opening.

4. A device of the character described comprising a flat body portion, a knife provided with a cutting edge on one side, a low part in the body portion adjacent the cutting edge of said knife, and a raised part in the body portion adjacent the opposite edge of said knife.

5. A device of the character described comprising a flat body portion provided with an elongated longitudinal opening and a bend adjacent one end, a knife removably mounted in the end of said body portion and having the free end thereof extending into said longitudinal opening, means for holding the knife in said end portion, a raised portion upon one side of said opening opposite the free end of said knife and a low portion upon the other side of said opening opposite the free end of said knife.

JAMES P. O'CONNELL.
